(Cl. D48—32)

To all whom it may concern:

Be it known that we, Harold W. Pilkey and Henry J. Keane, citizens of the United States, residing in the city of Detroit, county of Wayne, and State of Michigan, have invented a new, original, and ornamental Design for an Automobile Lamp Housing, of which the following is a specification, reference being had to the accompanying drawings, forming part thereof, in which:

Fig. 1 is a side elevational view of an automobile lamp housing showing our new design;

Fig. 2 is a top plan view thereof;
Fig. 3 is an end elevational view; and
Figs. 4, 5, 6 and 7 are vertical sections taken on the lines 4—4, 5—5, 6—6 and 7—7 respectively of Fig. 1.

We claim:

The ornamental design for an automobile lamp housing substantially as shown.

HAROLD W. PILKEY.

HENRY J. KEANE.
